UNITED STATES PATENT OFFICE.

VINCENT E. RUDLOFF, OF MAPLEWOOD, NEW JERSEY.

STAIR CONSTRUCTION.

Application filed January 21, 1922. Serial No. 530,805.

To all whom it may concern:

Be it known that I, VINCENT E. RUDLOFF, a citizen of the United States, residing at Maplewood, in the county of Essex and State of New Jersey, have invented certain new and useful Improvements in Stair Constructions; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to improvements in the construction of stairs; and the invention has reference, more particularly, to an improved construction and arrangement of elements for building fire-proof metallic stairs.

The invention has for its principal object to provide a novel arrangement and combination of elements for building metallic stair structures, whereby simplicity, strength and ornamental characteristics are attained with a minimum expenditure of cost and labor.

Another object of the invention is to provide novel means for operatively interconnecting the treads and risers of the stair structure to the stringers.

Other objects of this invention, not at this time more particularly enumerated, will be clearly understood from the following detailed description of the same.

With the various objects of this invention in view the same consists, primarily, in the novel stair structure hereinafter set forth; and the invention consists, furthermore, in the novel arrangements and combinations of the various devices and parts, as well as in the details of the construction of the same, all of which will be hereinafter more fully described, and then finally embodied in the claims appended hereto.

The invention is clearly illustrated in the accompanying drawings, in which:

Figure 1 is a perspective view of the novel stair structure made according to and embodying the principles of this invention, and in said view certain portions of the structure are shown broken away to show underlying parts and elements of the stair construction.

Figure 2 is a fragmentary transverse section showing a novel coupling element em-

ployed to interconnect a stair riser with the stringers of the structure.

Figure 3 is a fragmentary cross section of the outer stringer, showing the means for attaching and the relation of an ornamental facing member thereto.

Figure 4 is a fragmentary perspective of the riser coupling device.

Figure 5 is a fragmentary cross section and perspective of a modified form of outer stringer and ornamental facing member therefor.

Figure 6 is a fragmentary perspective view of a riser showing relation of the treads thereto.

Figure 7 is a perspective view of a novel tread supporting or reenforcing bracket or element for connection with the stringers.

Figure 8 is a perspective view of a modified form of said novel tread supporting or reenforcing bracket or element.

Similar characters of reference are employed in all of the hereinabove described views, to indicate corresponding parts.

Referring now to said drawings, the reference characters 9 and 10 indicate the stringers, which are inclined to extend, in parallel laterally spaced apart relation, from one floor level to another. Said stringers may be made of pressed sheet metal or channel iron, thereby providing the longitudinal outwardly projected right angle flanges 11 at their top and bottom edges, so that the body of the inner stringer is spaced from the building wall 12, and the body of the outer stringer is spaced from the ornamental facing member adapted to be associated therewith as will presently appear. Formed in said stringers are pairs of vertically aligned and spaced perpendicular slots 12, the same being spaced apart to occupy positions corresponding to the points at which the stair risers 13 are to be placed.

The means for attaching said risers 13 to and between the stringers 9 and 10, comprise a novel construction of interconnecting unit or anchor coupling, each consisting of a perpendicular metallic anchor plate 14 provided at one longitudinal edge with integrally formed coupling hooks 15, which extend outwardly from said edge in the plane of said anchor plate. Said coupling hooks 15 are spaced vertically apart to correspond to the vertical spacing of the members of said pairs of perpendicular slots 12 provided in the stringers 9 and 10. Since said slots

12 are of a length sufficient to permit the coupling hooks 15 of the anchor plates 14 to be entered or inserted therethrough, the builder or workman merely lines up the coupling hooks 15 with a pair of slots 12 and then thrusts the former through the latter, and thereupon thrusts downwardly upon the anchor plate 14 to engage the hook-ends 15' over the rear surface of the stringer body at the bottoms of said slots 12, thereby securing said anchor plate in perpendicular disposition and projecting at right angles from the plane of the outer surface of the stringer. The body of each anchor plate is provided with suitably disposed holes or perforations 16. When the interconnecting units or anchor couplings are thus attached to the stringers, the same are disposed in pairs, the members of which are respectively attached to the stringers in laterally opposed relation ready to receive the attachment of the risers 13 thereto. It will be apparent that the said interconnecting units or anchor couplings may be very quickly and easily attached to the stringers without necessity of employing tools or separable fastening means, such as nuts and bolts, screws, or the like, thus saving both labor and time. It will also be noted that the novel interconnecting units or anchor couplings are so constructed that the hooks 15 are self positioning, and that no bending, clinching or other similar operations are required to operatively associate the same with the stringers. The ends of the risers 13 are laid against the outer faces of said anchor plates 14, the same being punched with holes or perforations 17 to match or align themselves with the holes or perforations 16 provided in said anchor plates, so that when the riser is in position the stair builder or workman may insert through the matched openings or perforations 16 and 17 suitable fastening means 18, such as rivets, bolts or the like, whereby the riser is permanently secured in perpendicular position for extension between the stringers. Said risers 13 are preferably provided at their lower longitudinal margins with integrally formed outwardly projecting right angled or horizontal lower flanges or supporting lips 19, which extend toward the riser next below, while at their upper longitudinal margins, the risers are provided with integrally formed inwardly projecting right angled or horizontal upper flanges or supporting lips 20, which extend toward the riser next above. As thus arranged the flange or supporting lip 20 of one riser lies in a horizontal plane corresponding to the plane of said flange or supporting lip 19 of the next adjacent riser above, and consequently said flanges or supporting lips 19 and 20 are grouped in pairs between each pair of adjacent risers, so that the same are disposed to

support, a tread plate 21 in horizontal plane between the same, as shown. The tread plates 21 may be secured to said flanges or supporting lips 19 and 20 by screws, or any other convenient fastening means if desired. It will be understood that in stair structures of the lighter types, the said flanges or supporting lips 19 and 20 afford sufficient support for the tread plates, and consequently no additional support springing from or connected with the stringers is needed. In stair structures of the heavier types, it is desirable to provide a reenforcing support connected with the stringers, and to this end I have provided a novel construction of tread supporting or reenforcing bracket for attachment to the stringers, and adapted to engage and support the ends of the tread-plates 21 intermediate the flanges 19 and 20. This novel supporting or reenforcing bracket comprises a horizontal plate or body 22 preferably made of metal, and having its ends turned downwardly at right angles to the plane of said plate or body to form buttresses 23. Projecting rearwardly from said buttresses, and integrally formed therewith, are coupling hook portions 24. Formed in said stringers are pairs of horizontally aligned and spaced perpendicular slots 25, the same being spaced apart to occupy positions corresponding to the points at which the ends of said tread-plates 21 abut against the stringers. Said slots 25 are of a length sufficient to permit the coupling hooks 24 of the supporting or reenforcing brackets to be entered or inserted therethrough, so that the builder or workman merely lines up the coupling hooks 24 with a pair of slots 25 and then thrusts the former through the latter, and thereupon thrusts downwardly upon the plate or body 22 to engage the hook ends 24' over the rear surface of the stringer body at the bottoms of said slots, thereby securing the supporting plate or body 22 in horizontal disposition and projecting at right angles from the plane of the outer surface of the stringer. The plate or body 22 is provided with one or more perforations or holes 26. When said supporting or reenforcing brackets are thus attached to the stringers, the same are disposed in pairs, the members of which are respectively attached to the stringers in laterally opposed relation ready to receive the attachment of the ends of the tread-plates 21 thereto. It will be apparent, that in this case also, the said supporting or reenforcing brackets may be very quickly and easily attached to the stringers without necessity of employing tools or separable fastening means, such as nuts and bolts, screws, or the like, thus saving both labor and time in erecting the structure. It will also be clear that no bending, clinching or similar operations are necessary, since the coupling

hooks 24 automatically embrace the wall of the stringers when dropped over the lower end of the slotted portions thereof. The ends of the tread-plates 21 will rest upon and be supported by the plate or body 22, said ends being punched with holes or perforations to match those of the plate or body 22, so that suitable fastening means 27, such as rivets, bolts or the like, may be employed to firmly secure the tread-plates to said plates or bodies 22.

If desired the supporting or reenforcing brackets may be made in the modified form shown in Figure 8 in which case a single buttress portion 28 may project from the underside of the plate or body 29, intermediate the ends of the latter, and said buttress may be provided with a single coupling hook 30. In such case the stringers 31 are provided with a single slot 32 to receive said coupling hook 30, all as shown in said Figure 8.

After the risers 13 and tread-plates 21 have been connected, in the manner heretofore described, to and between the stringers 9 and 10, tread members or tops 33 may be secured upon the tread-plates in any suitable manner. Said tread members or tops 33 may be made of wood, slate, fibre, composition or of any other desired material. If desired the outer faces of the risers 13 may be covered with facing members (not shown) of material adapted to provide the desired finish and appearance.

When the stairs are open at one side, the outer or exposed stringer 10 may be provided with a facing plate or molding 34 of any desired conformation designed to produce a desired finish or ornamental effect. Said facing plate or molding 34 will cover the channel of the stringer 10, and may be secured in assembled relation to the latter by rivets 35, or other suitable fastening means.

In Figure 4 I have shown a modified form of outer or exposed stringer, together with a cap rail and facing plate or molding therefor. In this construction the outer or exposed stringer comprises a stringer plate 36, suitably punched to receive the anchor couplings and supporting brackets for attaching the risers and treads. Said stringer plate possesses no longitudinal flanges, but associated with its upper longitudinal edge is a cap-rail 37, having inwardly off set depending longitudinal flanges 38, against one of which said upper longitudinal marginal portion of said stringer plate is arranged. A facing plate or molding 39 is provided, the upper longitudinal marginal portion of which is secured against the other of said flanges 38 of the cap rail, while the lower longitudinal edge of said facing plate or molding 39 is provided with an inwardly projecting right angles flange

portion 40 which engages against the lower edge of said stringer plate to hold the facing plate or molding 39 properly off-set from the stringer plate.

The balusters 41 for supporting a hand rail, (not shown) may be attached to the upper flange of the stringer 10 in the one case, or to the cap-rail 37 in the other case.

I am aware that some changes may be made in the several arrangements and combinations of the devices and parts, as well as in the details of the construction of the same, without departing from the scope of this invention as set forth in the foregoing specification, and as defined in the appended claims. Hence, I do not limit my invention to the exact arrangements and combinations of the various devices and parts as described in said specification, nor do I confine myself to the exact details of the construction of said parts as illustrated in the accompanying drawings.

I claim:

1. In a stair structure, the combination with stringers provided with pairs of vertically alined and spaced vertical slots of anchor plates, each anchor plate having coupling hooks engageable in a pair of said slots to dispose said anchor plates in vertical disposition for projection from the opposed faces of said stringers, risers extending between said stringers and having their respective ends secured to laterally opposed anchor plates, and tread plates secured between said risers.

2. In a stair structure, the combination with stringers provided with pairs of vertically alined and spaced vertical slots of anchor plates, each anchor plate having coupling hooks engageable in a pair of said slots to dispose said anchor plates in vertical disposition for projection from the opposed faces of said stringers, risers extending between said stringers and having their respective ends secured to laterally opposed anchor plates, said risers having inwardly projecting flanges at their upper longitudinal edges, said risers having outwardly projecting flanges at their lower longitudinal edges, tread plates, and the upper flange of one riser forming in combination with the lower flange of the next riser above supports for a tread plate extending between said adjacent risers.

3. In a stair structure, the combination with stringers provided with pairs of vertically alined and spaced vertical slots and pairs of horizontally alined and spaced vertical slots intermediate said pairs of vertically alined slots of step structures comprising risers and tread plates, anchor plates, each anchor plate having coupling hooks engageable in a pair of said vertically alined and spaced slots to dispose said anchor plates in vertical disposition for pro-

- jection from the opposed faces of said stringers, supporting brackets, each supporting bracket having coupling hooks engageable in a pair of said horizontally alined and spaced slots to dispose said brackets in horizontal disposition for projection from the opposed faces of said stringers, said risers extending between said stringers and having their respective ends secured to laterally opposed anchor plates, and said tread plates extending between said stringers intermediate said risers and having their respective ends secured to laterally opposed brackets.
4. In a stair structure, the combination with stringers provided with pairs of vertically alined and spaced vertical slots and pairs of horizontally alined and spaced vertical slots intermediate said pairs of vertically alined slots of step structures comprising risers and tread plates, anchor plates, each anchor plate having coupling hooks engageable in a pair of said vertically alined slots to dispose said anchor plates in vertical disposition for projection from the opposed faces of said stringers, supporting brackets, each supporting bracket having coupling hooks engageable in a pair of said horizontally alined slots to dispose said brackets in horizontal disposition for projection from the opposed faces of said stringers, said risers extending between said stringers and having their respective ends secured to laterally opposed anchor plates, said tread plates extending between said stringers intermediate said risers and having their respective ends secured to laterally opposed brackets, said risers having inwardly projecting flanges at their upper longitudinal edges, said risers having outwardly projecting flanges at their lower longitudinal edges, and the upper flange of one riser and the lower flange of the next adjacent riser forming supports for the longitudinal marginal portions of intermediate tread-plates.
5. In a stair structure, a pair of laterally opposed stringers, vertical anchor plates for projection from the opposed faces of said stringers, said anchor plates having coupling hook means, said stringers having openings through which said coupling hook means may be passed to engage over the walls of said stringers adjacent to said openings, risers having their ends secured to opposed anchor plates, tread-plates, and said risers having means for supporting said tread plates intermediate adjacent risers.
6. In a stair structure, a pair of laterally opposed stringers, vertical anchor plates for projection from the opposed faces of said stringers, said anchor plates having coupling hook means, said stringers having openings through which said coupling hook means may be passed to engage over the walls of said stringers adjacent to said openings, horizontal supporting brackets for projection from the opposed faces of said stringers, said brackets having coupling hook means, said stringers having additional openings through which said bracket coupling hook means may be passed to engage over the walls of said stringers adjacent to said additional openings, risers adapted to be connected to said anchor plates for extension between said stringers, and tread-plates adapted to be connected to said brackets for extension between said stringers intermediate said risers.
7. In a stair structure, a pair of laterally opposed stringers, vertical anchor plates for projection from the opposed faces of said stringers, said anchor plates having coupling hook means, said stringers having openings through which said coupling hook means may be passed to engage over the walls of said stringers adjacent to said openings, horizontal supporting brackets for projection from the opposed faces of said stringers, said brackets having coupling hook means, said stringers having additional openings through which said bracket coupling hook means may be passed to engage over the walls of said stringers adjacent to said additional openings, risers adapted to be connected to said anchor plates for extension between said stringers, tread-plates adapted to be connected to said brackets for extension between said stringers intermediate said risers, and said risers having means for supporting said tread-plates at their longitudinal edge portions.
- In testimony, that I claim the invention set forth above I have hereunto set my hand this 17th day of January, 1922.
